UNITED STATES PATENT OFFICE.

WILLIAM A. WRIGHT, OF MASONVILLE, NEW JERSEY, ASSIGNOR OF ONE-HALF TO A. J. LAMBORN, OF PHILADELPHIA, PENNSYLVANIA.

SIGNAL-LANTERN.

No. 824,052.

Specification of Letters Patent.

Patented June 19, 1906.

Application filed January 21, 1905. Serial No. 242,101.

To all whom it may concern:

Be it known that I, WILLIAM A. WRIGHT, a citizen of the United States, residing at Masonville, in the county of Burlington and 5 State of New Jersey, have invented certain new and useful Improvements in Signal-Lanterns, of which the following is a specification.

This invention relates to certain new and 10 useful improvements in lanterns such as employed for railroad signaling and similar purposes, of which the following is a full, clear, and exact description.

One of the objects of this invention is to 15 provide a lantern wherein either the base and body or the base, body, and globe-guard may be detachably connected together.

Furthermore, this invention provides novel 20 means geared to feed the wick from the outer side of the lantern, obviating the necessity of moving the chimney or oil-cup thereof.

Another advantage lies in novel means 25 provided for detachably connecting the base and body whereby different bases may be employed, such as the bell or skeleton types; but the particular base shown is of the preferred form and one which will prevent accidental displacement of the lamp from the place where set.

Finally, this invention provides a lantern 30 which will be strong, durable, highly efficient in its use and operation, and comparatively simple and cheap in its manufacture.

In the drawings, forming a part of this 35 specification, reference will be had to the various views, wherein like numerals of reference indicate corresponding parts throughout, and in which—

Figure 1 is an elevation of the lantern, 40 showing the body in vertical section. Fig. 2 is a top plan view of a portion of the lantern, and Fig. 3 is a vertical section through the burner.

Reference-numeral 1 indicates the oil-cup, 45 provided on its periphery with tubular members or sleeves 2 to detachably receive the upper ends of the legs 3, to which is secured, by soldering or otherwise, a base 4, below which the pointed lower ends 6 of said legs 3 50 project to engage the surface on which the lantern is placed, thereby rendering accidental displacement thereof practically impossible. Thus by this construction the base is enabled to be removed from the body for

the application of a different base or for 55 cleaning purposes.

Rigidly attached to the outer side of the oil-cup is a rim 7, having an upturned flange 8, within which is received the base-ring 9 of the globe-guard. The said globe-guard comprises a plurality of wire sections 10, connected at their lower ends to said ring 9 and at their upper ends to the bell or dome 11, and connected to each of two diametrically opposite sections of said guard is a wire bail-ear 12, to which is connected one end of handle or bail 13. To detachably connect said ring to the rim 7 of said oil-cup, an inwardly-projecting lug or ear 14 is provided on the flange 8 of said rim 7, and to coact with this lug is secured a wire spring 15 on the opposite side of said rim, which spring when raised will permit the insertion of the ring thereunder. Near the upper portion of the oil-cup are arranged two spaced disks 16 and 17, the upper of which is formed with a plurality of orifices 18, through which the air enters from chamber 19 to feed the flame. This chamber 19 is formed by and between the said disks 16 and 17, and air enters through the ports 20 in the wall of the oil-cup at a point intermediate said disks.

For feeding the wick the following construction is provided: A wick-tube 21, comprising two plates 22 and 23, is passed through said disks 16 and 17 and projects above and below the same. Each end 24 of the plate 22 is bent to fit in the bent end 25 of the plate 23, by which it is securely held. The said ends or edges 25 of plate 23 are formed with lugs 26, through which pass a shaft 27, carrying on its outer end a gear 29, and intermediate said lugs or ears 26 three star-wheels 31 are arranged on the shaft and project and operate through slots in the plate 22 and engage the wick in said tube 21. Surrounding this tube is a funnel-shaped cup 30, spaced from the sides of said tube 21 and passed through said disks 16 and 17, to which it is secured, and the said cup forms a filling means for the oil-cup. The said star-wheels, it will be observed, overlie said cup 30, and one of them is engaged by a suitable catch or spring 32 to prevent unintentional rotation thereof. Meshing with the gear 29, aforementioned, is a gear 33, horizontally arranged in a housing 34, forming a bearing and shield for the wheel and its shaft 35.

This gear 33 when turned by the hand of the operator sets the gear 29 into operation, and consequently the wheels 31, thereby raising or lowering the wick.

5 When it is desired to light the lantern, the guard is removed after raising the spring 15, thus permitting access to the burner, and after the parts are reassembled the wick may be adjusted, as aforementioned, without the 10 removal of the globe, and to remove the base the legs are withdrawn from the sleeves 2 on the oil-cup.

Of course it is not the intention to limit this invention to the exact construction set 15 up, as various changes may be made in the details without material change or departure from the spirit and scope of the invention.

Having fully described the invention, what 20 is claimed as new and useful, and desired to be secured by Letters Patent of the United States, is—

1. A lantern comprising a body, a base, 25 legs secured on the inner face thereof and projecting above and below the same, and sleeves slidably and detachably connecting the projecting upper ends of said legs to said body.

2. In a lantern, a cup, disks arranged

therein, said cup and one of said disks 30 formed with air-ports, a wick-tube passing through the disks, a housing on the upper disk, a gear arranged therein projecting there-through and through the said cup, a shaft for said gear having a bearing in said housing 35 and said upper disk, and a wick-regulating means operated by said gear.

3. A lantern comprising a globe-guard, an oil-cup, a plurality of sleeves thereon, a base, 40 projections on said base removably received in said sleeves, and a rim secured to said oil-cup about said sleeves for receiving the globe-guard.

4. In combination with the oil-cup of a lantern, of two disks spaced to form an air-chamber in said oil-cup, a cup passing 45 through the disks, a wick-tube arranged in the cup and spaced therefrom forming a filling-space for said oil-cup, and wick-regulating means mounted above said cup and on 50 the side of said wick-tube.

In testimony whereof I affix my signature in presence of two witnesses.

WILLIAM A. WRIGHT.
